PREPARATION OF CHROMIUM COMPLEXES
OF β -DIKETONES

Kirman Taylor, Painesville, Ohio, assignor to Diamond Alkali Company, Cleveland, Ohio, a corporation of Delaware
No Drawing. Filed June 13, 1960, Ser. No. 35,437
12 Claims. (Cl. 260—438)

This invention relates to a method for the preparation of chromium organic compounds and more particularly relates to a method of preparing compounds, such as chromium acetylacetone, by the reaction of an anhydrous chromic chloride source material and an organic compound selected from the group consisting of organic compounds which undergo keto-enol tautomerism and organic compounds which have a hydroxy group positioned with regard to a coordinating atom so as to be capable of forming, with the chromium of the chromic chloride source material, a ring having 5-7 members.

In recent years, compounds of this type, and particularly chromium acetylacetone, have been the subject of a great deal of interest. This interest has been generated by the fact that these compounds are useful as additives in rubber, petroleum products, plastics, asphalts, paints, and the like, as catalysts and intermediates in organic syntheses and manufacturing processes and additionally as a source of chromium metal in plating or coating operations. In this latter application, inasmuch as these compounds are soluble in many organic solvents, they are particularly useful in processes involving chromium plating from organic solutions as well as being usable in vapor plating or coating processes.

However, the widespread use of these compounds has been somewhat stymied in that up to the present time no completely satisfactory method has been found by which they may be economically produced. In this regard, although many processes have been proposed for preparing these compounds, and in particular chromium acetylacetone, they all have one thing in common and that is that the preparation involves the use of an aqueous system.

In the earlier of these processes, the product yield, i.e., chromium acetylacetone, was very low, due principally to the coprecipitation of chromic hydroxide during the reaction. In later processes, efforts have been made to overcome this difficulty, such as for example, by using freshly precipitated hydrous chromium oxide as the source of chromium. However, this procedure necessitates an excess of the organic reagent, i.e., acetylacetone, which is the most expensive of the initial reactants, and is subject to further difficulties in that the hydrous chromium oxide must be prevented from aging if it is to be used. In a more recent process, described in U.S. Patent 2,823,217, an attempt is made to overcome the difficulties of the prior art processes by the addition of an alkali carboxy methyl dextran to the reaction mixture in order to prevent the precipitation of the chromium hydroxide. Although this latter process has seemingly been successful in that the precipitation of the chromium hydroxide is substantially prevented, it will be appreciated that this advantage is obtained only by the disadvantage of adding a somewhat costly chemical to the reaction mixture. Additionally, in this process although only stoichiometric quantities of the reactants are used, the yield of the chromium acetylacetone is only about 83% and difficulties are encountered in extracting the remaining portions of the organic reagent acetylacetone, from the water in order that it may be reused. Thus, it will be apparent that none of the prior processes have been completely

2

successful in overcoming the problems encountered in the production of these chromium organic compounds, and particularly chromium acetylacetone, primarily, because these processes have attempted to minimize the effect of the precipitation of chromium hydroxide rather than eliminating its cause.

It is, therefore, an object of the present invention to provide a novel method of preparing chromium acetylacetone and similar chromium organic compounds wherein no chromium hydroxide is produced to interfere with the production of the organic chromium compound.

A further object of the present invention is to provide a method for producing chromium acetylacetone and similar organic compounds wherein substantially stoichiometric amounts of the reactants can be used and substantially 100% yields of the chromium organic compound are obtained.

These and other objects will become apparent to those skilled in the art from the description of the invention which follows.

The method of the present invention envisions reacting an anhydrous chromic chloride source material and an organic compound selected from the group consisting of organic compounds which undergo keto-enol tautomerism and organic compounds which have a hydroxy group positioned with regard to a coordinating atom so as to be capable of forming, with the chromium of the chromic chloride source material, a ring having 5-7 members. The reaction is carried out in a non-aqueous solution by boiling or refluxing the reaction mixture, after effecting solubilization of the chromic chloride source material. By utilizing a non-aqueous solution for carrying out this reaction, there is no precipitation of chromium hydroxide and the problems previously encountered because of such precipitation are eliminated.

Exemplary of the organic compounds which undergo keto-enol tautomerism and may be used in the present method are the beta-diketones, such as acetyl- and benzoyl-acetone, and the beta-dioximes. Of the organic compounds capable of forming, with chromium, 5-7 membered rings, those compounds having a hydroxy group in a position alpha or beta to a coordinating group, such as an oxygen or nitrogen atom, are typical. Exemplary of such compounds are salicylic acid and its derivatives, 2-hydroxyazo compounds, 8-hydroxyquinoline, 1-hydroxyanthraquinone and alpha-hydroxy acids. Of these, excellent results have been obtained when using acetylacetone as the organic compound and for this reason, hereinafter, primary reference will be made thereto and to the preparation of chromium acetylacetone. It is to be understood, however, that the method of the present invention is applicable when using any of the organic compounds which will undergo a keto-enol tautomerism so that the specific references to acetylacetone and chromium acetylacetone are intended to be merely illustrative of the invention and not limiting.

The source of chromium for use in the present method may come from anhydrous chromic chloride or from organic complexes of anhydrous chromic chloride. Of the latter, the preferred is a complex of anhydrous chromic chloride and acetone. The preparation of this organic complex of anhydrous chromic chloride, as well as that of other similar complexes which may also be used in the present method, are set forth in my copending application Serial No. 828,009, filed July 20, 1959, now Patent No. 3,9076,833. As disclosed in this co-pending application, the complexes of chromic chloride have the formula $\text{CrCl}_3 \cdot \text{XR}$, wherein R is selected from the group consisting of ketones, aldehydes, alcohols, acid esters, amides, and amines and X is a number from 1 to 4, inclusive.

The method of the present invention may be illustrated generally by the following empirical formula:

In carrying out this reaction, it has been found that in order to assure that the reaction will proceed at a satisfactory rate, it is necessary to solubilize the chromic chloride by adding a catalyst, such as metallic zinc or chromous chloride to the reaction mixture. Excellent results have been obtained using chromous chloride as the catalyst and for this reason it is preferred in the present method. It has further been found, that if a freshly distilled acetylacetone is used in carrying out the reaction, the reaction will proceed at a satisfactory rate without the necessity of using a catalyst. However, as those skilled in the art will undoubtedly appreciate, some difficulties may be encountered in adapting the present process to commercial production, particularly, as a continuous process, where freshly distilled acetylacetone is required and for this reason it is preferred to carry out the reaction using a catalyst. It has also been found that when using a catalyst, the best results are obtained when the reaction mixture contains no moisture. It is believed that when there is moisture present in the system, the moisture acts to "poison" the chromous chloride catalyst, thereby rendering it non-effective in catalyzing the reaction.

Where the source of chromic chloride used in the present method is one of the organic complexes of chromic chloride, such as the acetone complex, it has been found that the reaction with acetylacetone progresses at a satisfactory rate without the necessity for the addition of a catalyst, such as chromous chloride or zinc. Inasmuch as it is believed that the catalyst serves primarily to solubilize the chromic chloride, since the organic complexes of chromic chloride are considerably more soluble than chromic chloride itself, no catalyst is needed. Additionally, in this reaction, the reaction mixture is boiled for a sufficient amount of time to distill off the acetone or other organic solvent.

Inasmuch as in the present reaction, the most expensive of the raw materials is the acetylacetone, it has been found to be desirable to carry out the reaction in benzene or a similar organic solvent, as the reaction medium. This is particularly true when the process is to be carried out continuously. In such an operation, substantially stoichiometric quantities of the acetylacetone are dissolved in benzene and following the reaction, the benzene containing any unreacted acetylacetone is recycled. In this manner, the need for recycling a large quantity of the relatively expensive acetylacetone is eliminated by recycling the relatively inexpensive organic solvent, such as benzene, in which is dissolved the small quantities of unreacted acetylacetone.

In carrying out the method of the present invention, the reaction mixture, consisting of the chromic chloride source material, e.g., anhydrous chromic chloride, and acetylacetone, in substantially stoichiometric amounts, are refluxed for a period of about 2 to 6 hours, preferably about 4 hours, in benzene in the presence of a catalyst, e.g., chromous chloride. The amount of catalyst used is not in excess of about 1% by weight of the total reaction mixture, excluding the benzene, and generally is only about 0.2% by weight of the total reaction mixture. The chromium acetylacetone thus formed is recovered by recrystallization from benzene and washed with an aqueous solution of ammonium hydroxide. The chromium acetylacetone thus recovered is found to be quite stable, undergoing decomposition only to the extent of about 1.2% by weight after heating for 50 hours at 191° C. and additionally is substantially water-insoluble, being soluble only to the extent of about 0.15%.

In order that those skilled in the art may better understand the method of the present invention and the man-

ner in which it may be practiced, the following specific examples are given.

Example 1

One hundred (100) grams CrCl_3 , 425 grams acetylacetone and about 0.5 gram CrCl_2 are refluxed in a 1-liter flask for about 2.5 hours. The mixture is cooled to room temperature and the violet chromium acetylacetone crystals are filtered off. The product is recrystallized from benzene, filtered and washed with ether and a dilute aqueous ammonical solution. The chromium acetylacetone is dried for 2 hours at 110° C. A yield of 206 grams of chromium acetylacetone (93.7%) is obtained, having the following analysis:

	Analysis	Theoretical	Actual
Percent Cr	14.90	14.70	
Percent Cl	0.00	<0.02	
Percent C	51.60	52.00	
Percent H	6.06	6.00	
Melting Point, °C	216	216	

Example 2

Twenty (20) grams CrCl_3 and 100 grams redistilled acetylacetone (B.P. 135-7° C.) are refluxed in a 300 ml. round bottom flask for about 4 hours. The mixture is cooled to room temperature and the chromium acetylacetone filtered off. The resulting product is then recovered as in Example 1. The yield of chromium acetylacetone, based on the CrCl_3 used, is substantially quantitative.

Example 3

Twenty (20) grams CrCl_3 , 400 ml. dry benzene, 45 ml. of acetylacetone and 0.1 gram CrCl_2 are refluxed in a 1-liter wide mouth Erlenmeyer flask for about 5 hours. All solvent is removed by evaporation and chromium acetylacetone crystals are washed with ether and an aqueous ammonical solution. Essentially a quantitative yield of chromium acetylacetone, based on the CrCl_3 used is obtained.

Example 4

Ten (10) grams of trichlorotriacetonechromium (III), prepared in accordance with the procedure of U.S. Ser. No. 828,009, are dissolved in 40 ml. of acetylacetone. The solution is heated to boiling and the acetone is distilled out. During the distillation the dark green liquor changed to a red-violet color and chromium acetylacetone crystals are precipitated. The mixture is cooled to room temperature and the chromium acetylacetone product recovered as in Example 1. The yield of chromium acetylacetone, based on the trichlorotriacetonechromium (III) used, is substantially quantitative.

While there have been described various embodiments of the invention, the methods described are not intended to be understood as limiting the scope of the invention, as it is realized that changes therewithin are possible, and it is further intended that each element recited in any of the following claims is to be understood as referring to all equivalent elements for accomplishing substantially the same results in substantially the same or equivalent manner, it being intended to cover the invention broadly in whatever form its principle may be utilized.

What is claimed is:

1. A method of preparing a chromium organic compound which comprises combining, under anhydrous conditions, a chromic chloride source material selected from the group consisting of anhydrous chromic chloride and organic complexes of anhydrous chromic chloride having the formula $\text{CrCl}_3 \cdot \text{XR}$, wherein R is selected from the group consisting of ketones, aldehydes, alcohols, acid esters, amides and amines and X is a number from 1 to 4, inclusive, with an organic compound selected from the group consisting of acetylacetone and benzoyl acetone in an organic solvent selected from the group consisting of

said organic compound and benzene, adding a catalyst selected from the group consisting of metallic zinc and chromous chloride, refluxing the thus formed reaction mixture for a period of time sufficient to effect a reaction between the chromic chloride source material and the organic compound to form a chromium organic compound and recovering the said organic chromium compound.

2. The method as claimed in claim 1 wherein the reaction medium is benzene.

3. A method of preparing chromium acetylacetone which comprises combining, under anhydrous conditions, a chromic chloride source material selected from the group consisting of anhydrous chromic chloride and organic complexes of anhydrous chromic chloride having the formula $\text{CrCl}_3 \cdot \text{XR}$, wherein R is selected from the group consisting of ketones, aldehydes, alcohols, acid esters, amides and amines and X is a number from 1 to 4, inclusive, with acetylacetone in an organic solvent selected from the group consisting of acetylacetone and benzene, adding a catalyst selected from the group consisting of metallic zinc and chromous chloride, refluxing the thus formed reaction mixture for a period of time sufficient to effect a reaction between the chromic chloride source material and the acetylacetone to produce chromium acetylacetone and recovering the chromium acetylacetone.

4. The method as claimed in claim 3 wherein the reaction medium is benzene.

5. A method of preparing chromium acetylacetone which comprises combining anhydrous chromic chloride and acetylacetone in an organic solvent selected from the group consisting of acetylacetone and benzene, adding a catalyst selected from the group consisting of metallic zinc and chromous chloride, refluxing the thus formed reaction mixture for a period of time sufficient to effect a reaction between the anhydrous chromic chloride and the acetylacetone to form chromium acetylacetone and recovering the chromium acetylacetone.

6. The method as claimed in claim 5 wherein the catalyst is chromous chloride.

7. The method as claimed in claim 6 wherein the reaction medium is benzene.

8. The method as claimed in claim 5 wherein the reaction medium is benzene.

9. A method of preparing chromium acetylacetone which comprises combining trichlorotriacetonechromium (III) and acetylacetone in an organic solvent selected from the group consisting of acetylacetone and benzene, heating the thus formed reaction mixture for a period of time sufficient to effect a reaction between the trichlorotriacetonechromium (III) and the acetylacetone and distill off acetone to form chromium acetylacetone and recovering the chromium acetylacetone.

10. A method of preparing chromium acetylacetone which comprises combining trichlorotriacetonechromium (III) and acetylacetone in benzene, heating the thus formed reaction mixture for a period of time sufficient to effect a reaction between the trichlorotriacetonechromium (III) and the acetylacetone and distill off acetone to form chromium acetylacetone and recovering the chromium acetylacetone.

11. A method of preparing chromium acetylacetone which comprises combining trichlorotriacetonechromium (III) and acetylacetone, heating the thus formed reaction mixture for a period of time sufficient to effect a reaction between the trichlorotriacetonechromium (III) and the acetylacetone and distill off acetone to form chromium acetylacetone and recovering the chromium acetylacetone.

12. A method of preparing chromium acetylacetone which comprises combining anhydrous chromic chloride and freshly distilled acetylacetone under anhydrous conditions, refluxing the thus formed reaction mixture for a period of time sufficient to effect a reaction between the chromic chloride and the acetylacetone to form chromium acetylacetone and recovering the chromium acetylacetone and recovering the chromium acetylacetone.
